UNITED STATES PATENT OFFICE.

ADELBERT AMES, JR., OF TEWKSBURY, MASSACHUSETTS.

PROJECTION APPARATUS.

1,235,752.

Specification of Letters Patent.

Patented Aug. 7, 1917.

Application filed October 11, 1916. Serial No. 125,108.

To all whom it may concern:

Be it known that I, ADELBERT AMES, Jr., a citizen of the United States, and resident of Tewksbury, in the county of Middlesex 5 and State of Massachusetts, have invented new and useful Improvements in Projection Apparatus, of which the following is a specification.

This invention relates to apparatus for projecting a concentrated beam of light sharply defined on at least one side, and more particularly the invention relates to a non-glare headlight for automobiles and the like which is adapted to project a concentrated beam of light along and below a horizontal plane through the apparatus without projecting substantially any light above said plane, thus producing a beam which is sharply defined on its upper side.

20 The invention is a continuation in part of each of the inventions disclosed in my applications, Sr. No. 102,085, filed June 6, 1916, Sr. No. 102,086, filed June 6, 1916, and Sr. No. 123,175, filed September 30, 1916, 25 certain features of the present invention having been disclosed in the former applications.

In application Sr. No. 102,085 I have disclosed a reflector in combination with a light source having portions vertically displaced relatively to a horizontal plane containing the axis of the reflector. As fully explained in the said application, the light radiating approximately horizontally from the portions of the light source displaced below the horizontal plane will strike the reflector at such angles as to be reflected upwardly unless some means is employed to avoid this result. Reference is hereby made to the 40 former application for a complete explanation of the cause of this upward glare and for a more detailed description of the means common to both this and the former application for avoiding upward glare due to 45 this cause.

In Sr. No. 102,086 I have also discussed this cause of upward glare and have disclosed certain means comprising deflectors disposed adjacent the horizontal plane, both 50 rearwardly and laterally of the light source, for downwardly deflecting the light radiating approximately horizontally in lateral rearward directions from the light source, this means also being employed in the present application.

In application Sr. No. 123,175, I have dis-

closed another method of avoiding upward glare resulting from light radiating approximately horizontally from the light source which comprises a novel positioning 60 of the light source having a V-shaped section with respect to the focus of the reflector. This method of positioning the light source is also employed in the present application in combination with certain other 65 features.

The preferred form of this invention comprises a paraboloidal reflector or other type of reflector adapted to project a concentrated beam of light in combination with a light 70 source which is positioned with respect to the focus of the reflector so as horizontally to project a concentrated beam of light from at least approximately that portion lying on one side of a horizontal plane containing 75 the axis of the reflector and refracting means positioned in the latter portion of the reflector for downwardly deflecting the light which is reflected upwardly from this portion of the reflector. The refracting means is preferably positioned in front of substantially the upper half of the reflector in such manner that the light reflected from this portion of the reflector is downwardly deflected to relatively near portions of the 80 roadway, the lower half being unobstructed whereby it may reflect a concentrated beam 85 horizontally.

I am aware that there is in use at the present time certain so-called non-glare 90 headlights which employ refracting means in front of paraboloidal reflectors. In one of these headlights the refracting means is in the form of prisms extending entirely across the front of the reflector. With this 95 construction it is impossible to obtain a beam of light whose upper side is sharply defined, that is, a beam of light wherein the transition from concentrated light to darkness is relatively sharp. If the prisms are designed 100 downwardly to deflect the light a sufficient amount to eliminate upward glare, it is impossible to obtain sufficient light in a horizontal direction to illuminate distant portions of the roadway; if the prisms are so 105 designed that the light is deflected downwardly only slightly thereby obtaining a fairly concentrated beam of light in a horizontal direction, it will be found that a great deal of light is reflected upwardly, 110 resulting in a decided glare effect. This is due to the fact that light from certain por-

tions of the reflector is reflected upwardly to a greater extent than the light from other portions; and, to eliminate downward glare, at the same time preserving a concentrated 5 horizontal beam of light, it is necessary downwardly to deflect only the portion of the light which is reflected upwardly. In the type of apparatus referred to all of the light whether reflected upwardly, or horizontally, or downwardly, is deflected downwardly by the refracting means, the effect 10 being somewhat similar to tilting the apparatus downwardly which, while it may avoid upward glare, will not afford a concentrated 15 horizontal beam of light capable of illuminating distant portions of the roadway.

In another type of apparatus heretofore employed, the refracting means is arranged to cover only a portion of the front of the 20 headlight. The defects of this type are similar to those described above. Furthermore, this apparatus has not been designed downwardly to deflect in a sufficient degree the light radiating approximately horizontally 25 from the light source and striking the reflector adjacent the horizontal plane containing its axis; and therefore does not eliminate upward glare due to the causes described in my former application Sr. No. 30 102,085. Moreover, in this type of reflector, as well as in the type above referred to, no provision has been made for the prevention of upward glare resulting from the light which is reflected from the inside of the 35 transparent container surrounding the light source, when employing the ordinary incandescent lamp or other lamp having a transparent container surrounding the light source.

40 The principal object of this invention is to provide apparatus having a reflector adapted to project a concentrated beam of light, a light source so disposed with respect to the focus of the reflector that a concentrated beam of light is directly projected from that portion of the reflector lying on one side of the horizontal plane containing the axis of the reflector, and having means for downwardly deflecting substantially all 45 light upwardly reflected from the reflector. This I preferably accomplish by employing a series of prisms covering substantially that portion of the reflector lying on the one side of the horizontal plane and also covering the portion of the reflector lying 50 adjacent the said horizontal plane from which light is upwardly reflected due to portions of the light source being vertically displaced from the said plane, as above described, although the object may be otherwise attained as will hereinafter more fully and at large appear.

Another object of the invention is so to dispose the light source with respect to the 65 focus of the reflector that the upward re-

flection of light radiating approximately horizontally from the source is minimized, if not entirely eliminated, when using refracting means as above referred to.

Another object of the invention is to utilize in combination with refracting means in front of a portion of the reflector, a transparent container for the light source which is so shaped and positioned with respect to the light source that substantially no light 70 is reflected from its inner surface in such manner as to be projected upwardly. If a spherical bulb is employed it must be so placed with relation to the light source that no rays from the source are reflected from 75 the inside of the bulb in such manner as to cross the horizontal plane containing the axis of the reflector on the side of the focus opposite from the light source. That is, if the lower half of the reflector is used directly to project a concentrated beam of 80 light, no rays should be reflected downwardly from the inner surface of the upper half of the lamp bulb in such manner as to pass in front of the focus of the reflector, 85 the light source being positioned behind the focus when the lower half of the reflector is used directly to project the concentrated beam. If the upper half of the paraboloidal reflector is employed directly to project the 90 concentrated beam, the lamp bulb should be so shaped and positioned with respect to the light source that no light is reflected from the inner surface of the lower half of the bulb which will cross the aforesaid horizontal 95 plane in the rear of the focus, the light source being positioned in front of the focus when employing the upper half of the reflector directly to project the concentrated beam. 100

In the accompanying drawings,—

Figure 1 is a vertical longitudinal section of one embodiment of my invention;

Fig. 2 is a front elevation of the apparatus shown in Fig. 1;

Fig. 3 is a vertical longitudinal section of another form of the invention;

Fig. 4 is a front elevation of the apparatus shown in Fig. 3;

Fig. 5 is a transverse vertical section taken 115 on the line 5—5 of Fig. 3;

Fig. 6 is a vertical longitudinal section of another embodiment of the invention;

Fig. 7 is a front elevation of the apparatus shown in Fig. 6;

Fig. 8 is a vertical longitudinal section of still another species of the invention; and

Fig. 9 is a vertical longitudinal section of apparatus in which the light source is improperly positioned with respect to the center of the lamp bulb. 120

The apparatus shown in Figs. 1 and 2 comprises a paraboloidal reflector P having its focus at f, a lamp bulb B having a V-shaped light source 2 positioned behind the 125 130

5 focus with its apex in the focus, the center *c* of the bulb being located slightly in front of the focus of the reflector. The series of prisms 3 are arranged substantially concentrically with the axis of the reflector and they extend down to the line 4. Below the line 4 the transparent front cover is frosted as indicated at 6, the frosted portion extending somewhat below the lowermost point of 10 the light source and having a depending portion 7 at the center.

Owing to the fact that the light source 2 is positioned behind the focus *f* of the reflector *P* substantially all of the light striking 15 the lower half of the reflector is reflected in or below a horizontal direction as indicated by ray 8. However, the light radiating upwardly from the light source is reflected upwardly, as indicated by ray 9, but 20 by virtue of the prisms 3 the upwardly reflected light is downwardly deflected sufficiently to be projected downwardly, as indicated by ray 11. The light radiating approximately horizontally from the leg of the 25 light source which is positioned below the horizontal plane containing the axis of the reflector ordinarily is reflected upwardly from the portions of the reflector just below and just above the said horizontal plane, 30 as fully described in my application Sr. No. 102,085. But, in order to prevent this light from being projected upwardly, the frosted glass is provided, the portion 7 being provided in the center to diffuse light reflected 35 upwardly from the portion of the reflector in the rear of the light source and below the axis owing to the fact that upward glare results from portions displaced farther below the aforesaid horizontal axial plane in 40 the rear of the light source than at the other sides thereof.

The apparatus shown in Figs. 3 and 4 is similar to that shown in Figs. 1 and 2 except that the prisms 12 are disposed horizontally 45 instead of concentrically with the axis of the reflector and that, instead of the frosted glass portions 6 and 7, the prisms 12 are extended downwardly to cover the same portion of the front of the apparatus as covered by the frosted glass in Figs. 1 and 2. Furthermore, the center *c* of the lamp bulb *B* is positioned behind instead of in front of the filament. A depending apron 13, which may be either reflecting or non-reflecting, 50 and which has narrow portions 14 fitting around the sides of the lamp bulb, may be provided, the portions 14 corresponding to the means disclosed in my application Sr. No. 102,086 for preventing light radiating 55 laterally from the light source from being reflected upwardly.

The glass prisms 12 are arranged to extend below the horizontal plane containing the axis of the reflector only a sufficient 60 amount downwardly to deflect all the light

which is reflected upwardly from the portions of the reflector adjacent the horizontal plane due to portions of the light source being vertically displaced below the plane. The apron 13 and bands 14 are arranged to 70 prevent from being reflected upwardly the light which radiates approximately horizontally from the light source and which would otherwise be reflected upwardly from the portions of the reflector adjacent the horizontal plane. This is accomplished either by deflecting this light downwardly as indicated by ray 16 in Fig. 3, or by ray 17 in Fig. 5, or by absorbing the light and thereby preventing its being reflected upwardly. 75

The members 13 and 14 accomplish the same result as the portion of the prisms 12 lying adjacent the horizontal plane, and if properly designed either means is alone sufficient, although it may sometimes be desirable to employ both means in combination in order more certainly to eliminate all upward glare. The difference between the operation of members 13 and 14 and the lower portion of the prisms is that the members 13 80 and 14 act upon the light which radiates horizontally from the light source before it strikes the reflector, whereas the prisms act upon this light after it strikes the reflector and is reflected upwardly. 85

Referring again to the position of the light source with respect to the container therefor, it is noted that any ray of light which is reflected from the inner surface of the lamp bulb, such as ray 18 in Fig. 1 or ray 19 in Fig. 3, passes back through the bulb on the side of the center of the bulb opposite to the point of the light source from which the ray emanated and at a distance from the center equal to the distance from the center to the ray emanating from the source. If a spherical bulb is employed the light reflected from the inner surface of the bulb is brought to a focus as indicated at 22, the result being the same as if a second light 100 source of weak intensity were positioned at 22. With the light source, the focus of the reflector, and the center of the container relatively disposed as in Fig. 1, all rays reflected from the upper half of the lamp bulb 105 pass downwardly in front of the focus and are reflected upwardly as indicated at 21, thus resulting in upward glare. The light reflected from the surface of the lower half of the container likewise passes in front of the center *c* and therefore in front of the focus *f*, but this light is unobjectionable inasmuch as it is reflected downwardly from the upper half of the reflector and therefore comes as if from in front of the focus. 110

The correct position of the light source with respect to the center of the lamp bulb is that shown in Fig. 3, Fig. 1 merely illustrating the fact that upward glare results from an improper relative positioning of the 115 120 125 130

parts. Where the center *c* of the lamp bulb *B* is behind the light source the rays of light, such as ray 19, which are reflected from the upper half of the bulb, pass behind the center *c*, and therefore behind the focus *f*, and consequently are reflected downwardly from the lower half of the reflector, as indicated at 23. The rays of light radiating upwardly from the image or virtual source 22, such as ray 24, are projected downwardly due to the action of the prisms 12, as indicated at 25, notwithstanding the fact that the rays are reflected upwardly from the reflector *P*.

The apparatus shown in Figs. 6 and 7 comprises a paraboloidal reflector *P*, prisms 26 covering substantially the upper half of the front of the reflector, and a V-shaped light source 27 having its lower leg disposed along the axis of the reflector, its apex in the focus *f*, and its other leg disposed above the axis. While I have shown a V-shaped light source any light source having a V-shaped section, as for example, a conical light source formed by a spiral filament, will answer the purpose, the requirement being that the filament shall not extend below the horizontal plane containing the axis or in front of a transverse plane through the line 28 which passes through the focus *f* and the lowermost central point of the reflector, all as fully described in my copending application Sr. No. 123,175.

With the light source shaped and disposed as just described and with the various parts accurately manufactured and assembled, substantially no light is reflected upwardly from the lower half of the reflector, it being unnecessary therefore to extend the prisms 26 below the horizontal plane containing the axis of the reflector.

The embodiment of the invention illustrated in Figs. 6 and 7 is particularly efficient inasmuch as the particular disposition of the light source with respect to the focus 45 of the reflector is such that a very concentrated beam of light is projected in and below a horizontal direction from the entire lower half of the reflector. The center *c* of the bulb *B* is preferably disposed behind the 50 light source as above described so that the image 29 of the light source 27 will be formed behind the focus *f* and no light therefrom will be projected upwardly.

In Fig. 8 I have illustrated the fact that 55 the apparatus may be employed in a position inverted with respect to that shown in the precedent figures. With this arrangement the light source 31 should be positioned in front of the focus *f* of the paraboloidal reflector *P* inasmuch as the upper half of the reflector is employed directly to reflect the concentrated beam in and below a horizontal direction. The apron 32 corresponding to the apron 13 shown in Fig. 3 65 is mounted on the ferrule to extend up-

wardly instead of downwardly in order to shield the central portion of the reflector lying just above the horizontal plane containing the axis, so that rays of light such as 33 will be reflected downwardly as at 34, 70 instead of upwardly as at 36 as in the absence of the apron 32. Bands 37 are mounted on the apron 32 to extend on either side of the lamp bulb, as described in connection with Figs. 3 and 5, whereby the light radiating approximately horizontally from the light source will be prevented from striking the reflector *P* so as to be reflected upwardly.

Inasmuch as the light source 31 is positioned in front of the focus *f*, the light striking the lower half of the reflector is reflected upwardly and prisms 38 function downwardly to deflect this light sufficiently to prevent its being projected upwardly. 35 The center *c* of the bulb *B* is positioned on the side of the light source opposite to the focus, as in Figs. 3 and 6, but inasmuch as the light source is in front of the focus the center *c* is positioned in front of the focus 40 and the image of the source will be formed at 39 in front of the focus *f*, whereby rays therefrom such as ray 41, for example, are reflected downwardly from the upper half of the reflector, and the rays radiating 45 downwardly therefrom, such as ray 42, are refracted by the prisms so that they are not projected upwardly.

While the light source must be positioned with respect to the center of the bulb so that 100 the image of the source is formed on the same side of the focus as the source itself, as above explained, the image must not be formed too far from the focus. As illustrated in Fig. 9 for example, the light 105 source 43 is positioned a considerable distance in front of the center *c* of the bulb *B* whereby the virtual image is formed at 44 at a position remote from the focus *f* of the reflector *P*. With the image so far 110 behind the focus, the rays therefrom, such as rays 46, are reflected so as to diverge widely from the axis of the reflector. While this is not objectionable in so far as the lower 115 half of the reflector is concerned, the light reflected upwardly from the upper half of the reflector may diverge so widely from the axis that the prisms 47 can not sufficiently refract them to bring them into or below a horizontal direction, inasmuch as 120 the laws pertaining to the critical angles of reflection are such that, if the slope of the rear faces of the prisms are made too great, light is reflected from the rear faces 125 of the prisms instead of passing into the prisms, in which event the light is thrown to the upper half of the reflector, a large part of which is wasted and a part of which finds its way to the lower half of the reflector at such angles as to be reflected 130

upwardly therefrom. Furthermore, even though the critical angle is not passed the slope of the faces of the prisms should not be made too great since it is desirable to 5 throw the portion of the light which is deflected by the prisms to intermediate portions of the roadway and not wholly to portions immediately in front of the vehicle. Moreover, the weight of the prisms increases 10 in proportion to the increase in the slope of the faces, and the slope should be maintained as low as possible for this further reason.

It will be noted that in each embodiment 15 of this invention a concentrated beam of light is directly projected from substantially half of the reflector in and below a horizontal direction in such manner as to illuminate distant portions of the roadway, 20 that light is downwardly deflected from substantially the other half of the reflector to near and intermediate portions of the roadway, and that light radiating approximately horizontally from the portions of the 25 light source which are vertically displaced with relation to the horizontal plane containing the axis of the reflector, is prevented from being projected upwardly.

Only that light which would otherwise 30 be reflected upwardly is diffused or refracted downwardly, and all of the light which is reflected in or below a horizontal direction is permitted to be directly projected to distant portions of the roadway, this result 35 being more effectually attained by making the outline of the lower edge of the prisms irregular. This not only effects a saving of light owing to the fact that only the objectionable upwardly reflected light is acted 40 upon, but it affords a beam of light which is sharply defined on its upper side and which will therefore more effectively illuminate distant portions of the roadway. Furthermore, if the parts are accurately manufactured 45 and are carefully assembled the projected beam of light is not only sharply defined on its upper side, but it is sharply defined by a plane, namely, the horizontal plane containing the axis of the reflector.

50 It is to be understood that the words above, below, upwardly, downwardly, etc., are employed in the specification and claims merely in a relative sense for the sake of convenience and conciseness, and that the apparatus 55 is not limited to use in the sole position or for the sole purpose described.

I claim:

1. Projection apparatus comprising a concave reflector adapted to project a concentrated beam of light along its axis, a light source having at least two substantial dimensions, the light source being so positioned with respect to the focus of the reflector that light is reflected from approximately half of the reflector substantially

parallel with a horizontal plane containing said axis, and refracting means arranged downwardly to deflect substantially all light reflected upwardly from the reflector, whereby a concentrated beam of light may 70 be projected a considerable distance along a roadway without producing upward glare.

2. Projection apparatus comprising a reflector adapted to project a concentrated beam of light along and below a horizontal plane containing its axis, a light source having portions vertically displaced with respect to said plane and being positioned with respect to the focus of the reflector so as to project a concentrated beam of light substantially parallel with said plane, and refracting means for downwardly deflecting to near and intermediate portions of the roadway part of the light reflected from the reflector including substantially all light which would otherwise be projected upwardly, whereby a concentrated beam of light sharply defined on its upper side may be projected substantially horizontally. 85

3. Projection apparatus comprising a substantially paraboloidal reflector, refracting means covering that portion of the front of the reflector lying on one side of a horizontal plane containing the axis of the reflector, and a light source positioned substantially 95 wholly above said plane along the axis on one side of the focus of the reflector, the remaining portion of the front of the reflector being unobstructed, whereby a concentrated beam of light is projected along and below said plane from the unobstructed portion of the reflector and light from the other portion of the reflector is deflected downwardly by the refracting means.

4. Light projection apparatus comprising 100 a concave reflector and a light source, the reflector being so shaped and the light source being so positioned on one side of a transverse plane through the focus of the reflector as to project from the portion of the reflector lying on one side of a horizontal plane containing the axis of the reflector a concentrated beam of light along said plane, refracting means downwardly to deflect the light reflected from other portions of the reflector, and a transparent container for the light source, the container being so shaped and the light source being so positioned within the container as to prevent substantially any light reflected from the inner surface of the container being reflected to the reflector in such manner as to cross said horizontal plane on the side of said transverse plane opposite to the light source. 115

5. Projection apparatus comprising a reflector adapted to project a concentrated beam of light along its axis, a light source having portions vertically displaced from a horizontal plane containing the axis of the reflector, the light source being positioned 120 125

- with respect to the focus of the reflector so that at least approximately half the light reflected from the reflector is directly projected along and below said horizontal plane, 5 means for downwardly deflecting the light reflected from other portions of the reflector including substantially all light which otherwise would be projected upwardly, and a transparent container for the light source, 10 the container being so shaped and positioned that the light reflected from the inner surface thereof to the reflector strikes the reflector at such angles as to be projected downwardly.
- 15 6. Projection apparatus comprising a substantially paraboloidal reflector, a light source having portions vertically displaced from a horizontal plane containing the axis of the reflector, the light source being shaped 20 and positioned with respect to the focus of the reflector so that light is directly projected substantially parallel with said plane from substantially all of that part of the reflector lying below said plane, and a re- 25 fractor for downwardly deflecting to near and intermediate portions of the roadway the light reflected from the other portions of the reflector.
7. Projection apparatus comprising a sub- 30 stantially paraboloidal reflector, a light source having portions vertically displaced from a horizontal plane containing the axis of the reflector, the light source being positioned with respect to the focus of the re- 35 flector so that light is directly projected sub- stantially parallel with said plane from sub- stantially all of the reflector lying on one side of said plane, and a refractor for down- 40 wardly deflecting to near and intermediate portions of the roadway the light reflected from the other portions of the reflector.
8. Projection apparatus comprising a sub- 45 stantially paraboloidal reflector, a light source being disposed on one side of the focus of the reflector along the axis of the reflector with one end in the focus so that substantially all light incident to the reflector on one side of a horizontal plane containing the axis of the reflector is directly projected substantially parallel with said horizontal plane to distant portions of the roadway, refracting means for downwardly deflecting to nearer portions of the road- 50 way substantially all light incident to the reflector on the other side of said plane, portions of the light source being vertically dis- 55 placed from said plane, and means to prevent light radiating approximately horizon- 60 tally from said displaced portions from being projected upwardly.
9. Projection apparatus comprising a sub- 65 stantially paraboloidal reflector, a light

source having a V-shaped section, the light source being disposed on one side of the focus of the reflector along the axis of the reflector with one end in the focus so that substantially all light incident to the reflector on one side of said plane will be directly projected substantially parallel with said horizontal plane to distant portions of the roadway, and refracting means for downwardly deflecting to nearer portions of the roadway substantially all light incident to the reflector on the other side of said plane.

10. Projection apparatus comprising a substantially paraboloidal reflector, a light source having a V-shaped section, the light source being disposed on one side of the focus of the reflector along the axis of the reflector with one end in the focus and being disposed substantially wholly on one side of a horizontal plane containing the axis of the reflector, whereby substantially all light incident to the reflector on one side of said plane will be directly projected along and below said horizontal plane to distant portions of the roadway, and refracting means for downwardly deflecting to nearer portions of the roadway substantially all light incident to the reflector on the other side of said plane.

11. Projection apparatus comprising a reflector adapted to project a concentrated beam of light, a light source disposed substantially wholly on one side of a transverse plane through the focus of the reflector and substantially wholly on one side of a longitudinal plane containing the axis of the reflector, so that light is directly projected substantially parallel with said horizontal plane from the portion of the reflector disposed on one side of said longitudinal plane, and means for deflecting the light reflected from other portions of the reflector toward said horizontal plane.

12. Projection apparatus comprising a concave reflector adapted to project a concentrated beam of light along its axis, a light source having at least one substantial dimension, the light source being so positioned with respect to the focus of the reflector that light is reflected from approximately half of the reflector substantially parallel with and below a horizontal plane containing said axis, and refracting means arranged downwardly to deflect substantially all light reflected upwardly from the reflector, whereby a concentrated beam of light may be projected a considerable distance along a roadway without producing upward glare.

Signed by me at Boston, Massachusetts, this third day of October, 1916.

ADELBERT AMES, JR.
